DESIGN FOR A COOKY JAR

Lester M. Chace, Pekin, Ill., assignor to Ludowici
Celadon Company, Chicago, Ill., a corporation

Application November 8, 1943, Serial No. 111,630

Term of patent 7 years

(Cl. D58—25)

To all whom it may concern:

Be it known that I, Lester M. Chace, a citizen of the United States, residing at Pekin, in the county of Tazewell and State of Illinois, have invented a new, original, and ornamental Design for Cooky Jars, of which the following is a specification, reference being had to the accompanying drawing, forming part thereof.

I claim:

The ornamental design for a cooky jar, substantially as shown.

LESTER M. CHACE.
